UNITED STATES PATENT OFFICE.

CHARLES H. PEARSE, OF BELOIT, WISCONSIN, ASSIGNOR OF ONE-HALF TO CHARLES H. WILLIAMS, OF BELOIT, WISCONSIN.

SKIRT-GAGE.

1,112,651.

Specification of Letters Patent.

Patented Oct. 6, 1914.

Application filed July 17, 1913. Serial No. 779,526.

To all whom it may concern:

Be it known that I, CHARLES H. PEARSE, a citizen of the United States, residing at Beloit, in the county of Rock and the State 5 of Wisconsin, have invented certain new and useful Improvements in Skirt-Gages, of which the following is a specification.

This invention relates to skirt gages for use in obtaining the correct length of a skirt 10 in the making or fitting of it to a form or wearer.

The object of the invention is to provide a novel means for gaging the length of the skirt without the use of any chalking or 15 marking of the skirt material; and further, a means for securing and maintaining the bottom edge of the skirt at its gaged or determined length, in a hem, whereby the hem may be basted in its said gaged position and 20 placed in condition for sewing.

In the accompanying drawings: Figure 1 illustrates the figure of a woman having the length of her skirt gaged with my improved means. Fig. 2 is a view in perspective of the 25 gaging frame. Fig. 3 is a fragmentary view in vertical section showing the means for determining the length of the skirt. Fig. 4 is a perspective view illustrating a portion of the skirt detached from the frame.

The gaging frame is in the form of an 30 annular band 5 having inset studs 6 which carry vertically the legs or supports 7 adjustable by screws 8, whereby the band 5 may be adjusted to varying heights from the 35 floor.

In determining the correct length of a skirt, the wearer will stand within the enclosure of the band 5 so that the lower edge 40 of the skirt is disposed about said band, (the band having been adjusted and set so that its lower edge 9 represents the distance from the floor at which the skirt is to be gaged) and the edge 10 of the skirt which depends below said edge 9 of the band is turned in- 45 ward and upward to lie adjacent the inner side of the band, and spring clasps 11 having two clasping members are affixed to said edge 9 to impinge the edge 10 of the skirt in its said adjusted position, the placing of 50 these clasps about the entire periphery of the band thus determining positively the length of the skirt. The skirt is then re-

moved from the gaging frame without displacing the clasps 11 from their clasped relation with the upturned edge 10, the clasps 55 slipping off of the edge 9 by pulling of the skirt material downward; and thus it will be noticed, Fig. 4, that these clasps maintain the predetermined length of the skirt by the forming of a hem at the bottom edge of the 60 skirt by the upturned edge 10. This hem may be now basted in position and the clasps removed to allow the proper sewing and finishing of the skirt.

When it is desired that the length of the 65 skirt shall be within close proximity of the floor, a block 12 is placed on the floor within the band 5 and the wearer stands upon this block, the top of the block representing the floor level; and thus the band 5 may be set 70 at a nearer distance to the represented floor level so that the clasps do not conflict with the actual floor level, allowing them to be more easily attached. My improved means may also be used with models or forms in 75 which the skirt is placed on the form which is located above and within the gage frame, and the proper length secured in a manner such as above described.

With this means of gaging the length of 80 a skirt it will be noticed that the skirt material is not marked or chalked as in commonly used methods, and that the final hem, fixed at its desired position is secured, thus 85 accomplishing two objects in the same operation.

I claim as my invention:

A skirt gage, comprising, an annular member, supports connected thereto to hold the member elevated from the floor level, 90 and detachable clasps engaging the lower edge of a skirt folded upon a rim of said annular member and removable from the rim by the removal of the skirt therefrom, whereby said clasps maintain the said edge 95 of the skirt folded as in a hem.

In testimony whereof I have hereunto set my hand in presence of two subscribing witnesses.

CHARLES H. PEARSE.
